FOOT CONTROL FOR SHANK AND BIT PUNCHES

Filed Nov. 3, 1925

2 Sheets-Sheet 2

UNITED STATES PATENT OFFICE.

HARRY V. HAIGHT, OF SHERBROOKE, QUEBEC, CANADA, ASSIGNOR TO INGERSOLL-RAND COMPANY, OF JERSEY CITY, NEW JERSEY, A CORPORATION OF NEW JERSEY.

FOOT CONTROL FOR SHANK AND BIT PUNCHES.

Application filed November 3, 1925. Serial No. 66,622.

This invention relates to shank and bit punches, but more particularly to a foot controlling device for a shank and bit punch of the fluid actuated type.

5 The objects of the invention are to definitely limit the time required for advancing and retracting the punching mechanism to and from the drill steel, to automatically reverse the direction of travel of said punching mechanism and to automatically shut off the pressure fluid to the percussive and feeding element after the punching operation is completed.

10 Other objects will be in part obvious and in part pointed out hereinafter.

The invention consists of the combinations of elements, features of construction and arrangement of parts having the general mode of operation substantially as hereinafter described and more particularly pointed out in the appended claims and illustrated in the accompanying drawings, in which

20 Figure 1 is an outlined view in elevation of a shank and bit punch and a foot control therefor mounted on a sharpening machine,

25 Figure 2 is an enlarged detail view in elevation and partly in section illustrating the position of the parts while the punch pin is being driven into the drill steel,

30 Figure 3 is a view similar to Figure 2 illustrating the position of the parts while the punch pin is being withdrawn from the drill steel, and

35 Figure 4 is a view of the valve chest and the valve showing the manner in which the cam cooperates with the valve for shutting off the supply of pressure fluid to the percussive and feeding elements of the punch.

40 Referring to the drawings, A indicates a shank and bit punch mounted slidably on a bar B and being provided with a punch pin C which is adapted to be driven into a drill steel D for the purpose of reforming

45 the bore adjacent the shank and bit ends of the drill steel. Any suitable mounting may be provided for the punch. In the present instance, the punch is shown secured to a sharpening machine for convenience of illustration, although the punch A may be used in connection with any suitable clamping device.

50 In the present instance a brace E forms a support for one end of the bar B and the

other end of the bar is suitably secured to a bracket F, which in turn is bolted to the sharpening machine G. The drill steel D may be clamped between the body of the sharpening machine and a reciprocatory cross head H and is limited against longitudinal movement in one direction by a stop J bolted or otherwise secured to the bracket F.

55 Within the percussive cylinder K of the punch A is a reciprocatory hammer piston L to deliver blows in a forward direction on an anvil block O which in this instance also serves as a chuck for the punch pin C which is preferably held within the anvil block O by means of a dowel pin P. Longitudinal movement of the anvil block O is in this instance limited by a shoulder O' formed on said anvil block. The piston L is of the differential type and in addition to driving the pin also controls the admission of pressure fluid to the end faces Q and R of a piston head S. In this instance the front end of the cylinder K is closed by a front cylinder washer T which is bored to receive a front head U.

60 Arranged slidably on the front head U is a cross head V which is bored to serve as a guide for one end of the anvil block O. A back head W forms a closure for the rearward end of the cylinder K and is bored to receive slidably an anvil block X arranged therein for the purpose of driving the punch pin C out of the drill steel D. Disposed slidably on the back head W is a cross head Y bored to receive 65 slidably an end of the anvil block X. The cross heads V and Y are preferably held in spaced relation with respect to each other by means of suitable spacers Z through which extend bolts b whereby the cross heads are clamped together in such a manner that they may slide in unison when pressure is applied to either end of the unit thus formed.

70 The rearward end of the piston L is constantly exposed to pressure fluid which enters said cylinder through a passage c. In this instance the passage c is also extended toward the forward end of the cylinder for admitting pressure fluid to the 75 face R of the piston head S. Pressure fluid to the front end of the cylinder is conveyed thereto through a passage d. In this

instance a port *e* forms a free exhaust for the pressure fluid and is controlled by the piston head *S*. The opening of the passage *c* to the rear end of the cylinder *K* is so arranged that pressure fluid passing therefrom into the cylinder will act against the inner face of the anvil block *X* and constantly tend to hold said anvil block out of the path of the piston *L* while the punch pin 10 *C* is being driven into the drill steel *D*.

Suitable means are usually provided in machines of this type for advancing the punch in the direction of the drill steel *D* and also for retracting the punch after the 15 punch pin *C* has penetrated the drill steel *D* to a sufficient depth for reforming the bore within the drill steel. To this end, a feeding mechanism comprising a feeding cylinder *f*, which is preferably formed integrally with the cylinder *K*, is provided with a piston *g* which is secured to the brace *E* and held stationary with respect thereto by means of a piston rod *h*. The free end of the piston rod *h* is preferably 20 screw threaded as illustrated to receive suitable nuts *j*, which in addition to holding the piston *g* stationary, also serve as a means for adjusting the position of said piston with respect to the cylinder *f*. A 25 back head *k* in this instance forms a closure for the rearward end of the cylinder *f* and is suitably bored as at *o* to guide the piston rod *h*.

In accordance with the present invention 30 a valve chest *p* is secured to the back head *k* and is provided with a longitudinal chamber *q* to receive slidably a pressure fluid controlling valve *r* having a stem *s* which extends exterior of the chamber *q* through 35 a cap *t* screwed to the end of a plug *u*. The plug *u* in this instance serves to limit the travel of the valve in one direction and is bored to receive a packing *v* which is held in position by the cap *t*. The valve *r* preferably 40 has a longitudinal bore *w* which is in constant communication with a source of pressure fluid supplied through ports *z* formed diagonally in one end of the valve, and through a connection *y* suitably secured 45 to the valve chest *p*. A pair of ports *z* and *2* in the valve *r* lead from the bore *w* to the periphery of the valve to register in one position of the valve with a passage *3* leading to the front end of the feeding cylinder 50 *f* and with a passage *4* leading from the chamber *q* to the passage *c*.

In another limiting position of the valve 55 the port *z* is adapted to register with the passage *4* and the port *2* in this position of the valve is adapted to register with a passage *5* leading to the rearward end of the feeding cylinder *f*. Exhaust passages *6* and *7* are formed in the valve chest *p* for 60 exhausting pressure fluid from the front 65 and rear ends of the feeding cylinder *f*

respectively. The passages *6* and *7* are so arranged with respect to the passages *3* and *5* leading to the ends of the cylinder *f* that when the valve is in position to admit pressure fluid to one end of the feeding cylinder 70 *f* the other end of the feeding cylinder will be opened to atmosphere. Communication between the passage *3* and the exhaust port *6* is in this instance afforded by an annular groove *8* near the upper end of the 75 valve *r*. A similar groove *9* is formed near the opposite end of the valve for establishing communication between the passage *5* and the exhaust port *7*. A plug *10* is in this instance screwed in the upper end of so the chamber *q* for the purpose of sealing 80 said chamber.

Disposed within the upper end of the valve *r* is a plug *12* which is provided with a small port *13* through which pressure fluid 85 may constantly pass from the interior of the valve to the end of the chamber *q*. Pressure fluid thus passing through the port *13* will pass into a hose connection *14*, which is in effect a pressure chamber. After the pressure fluid within the hose and the upper end of the chamber *q* becomes of sufficient value to overcome the pressure acting against the opposite end of the valve *r* the valve will 90 automatically be actuated to its other limit- 95 ing position.

To the end that the pressure fluid accumulated in the hose *14* may be released whenever it is desired to start the punch, a valve box *15* is secured to the opposite end of the 100 hose to receive a pressure releasing valve *16* normally held on its seat by a spring *17*. A plate *18* is secured to the upper end of the valve box and is held in position by a suitable nut *19* to support a treadle 105 hinged thereto at one end as at *21*. The valve box *15* is provided with a plurality of exhaust passages *22* for exhausting pressure fluid from the chamber or hose *14* when the valve *16* is unseated. In order that the 110 valve *r* may be automatically actuated to a neutral position, a cam *23* is arranged beneath the stem *s* to cooperate therewith for raising the valve *r* after the punching operation is completed. The cam *23* may be secured to the device in any suitable manner, but in this instance an upwardly extending 115 leg *24* of the cam is secured to the connecting rod *h* and the other end of the cam is secured to the body of the sharpening machine *G*. 120

In the operation of the device, assuming that the punch pin *C* is about to be driven into the drill steel *D* as illustrated in Figure 2, and assuming further that the valve *r* 125 is then in position shown in Figure 4, which would be the position of the valve while the machine is at rest. If then the operator presses his foot on the treadle *20* and opens the valve *16*, the accumulated pressure fluid 130

in the chamber or hose 14 will be exhausted to the atmosphere and permit the pressure acting against the opposite end of the valve *r* to raise said valve to the position shown 5 in Figure 2. In this position of the valve *r* the ports *z* and 2 will register with the passages 3 and 4 leading to the front end of the feeding cylinder *f* and to the cylinder *K* respectively to admit pressure fluid to said 10 cylinders. Pressure fluid thus admitted to the front end of the cylinder *f* will cause the punch to move toward the drill steel *D*. At the same time the piston *L* will deliver 15 blows against the anvil block *O* which will be automatically forced inwardly into the path of the piston by the resistance of the drill steel against the punch pin *C*. After the pressure fluid has been exhausted from the chamber 14 the operator may remove his 20 foot from the treadle 20 since the succeeding operations of the punch will be entirely automatic as will be explained hereinafter.

During the time that the punch pin *C* is being driven into the drill steel *D*, pressure 25 fluid will pass through the port 13 into the upper end of the chamber *q* and into the hose or chamber 14 and will build up sufficient pressure within the upper end of the chamber *q* to overcome the pressure acting against the 30 opposite end of the valve. The pressure fluid thus entrapped will automatically move the valve to its other or downward limiting position at about the time that the punch pin *C* has been driven into the drill 35 steel *D* to a sufficient depth to open the bore thereof. Upon reversal of the valve *r*, the port *z* will be moved into registration with the passage 4 leading to the cylinder *L* and the port 2 will register with the passage 5 40 leading to the rearward end of the feeding cylinder *f*. In this position of the valve *r* the front end of the feeding cylinder *f* will be placed in communication with the atmosphere through the port 6 and the annular groove 8. By thus automatically causing 45 the valve *r* to be actuated to its lowermost limiting position and thereby admitting pressure fluid to the rearward end of the cylinder *f*, the punch will automatically be 50 caused to travel rearwardly on the bar *B*. As the punch *A* starts in a rearward direction the resistance caused by the drill steel *D* on the punch pin *C* will momentarily hold said pin stationary until the cross head 55 *V* contacts with the shoulder *O'* of the anvil block *O*, thus also holding the cross heads *V* and *Y* momentarily stationary. Continued rearward travel of the punch will expose the inner face of the anvil block *X* to the 60 blows of the piston and thus drive the punch pin *C* out of the drill steel *D*. As the punch *A* approaches the rearward stopping position on the bar *B* the stem *s* of the valve *r* will slide over the cam 23 and raise said 65 valve to the neutral position illustrated in

Figure 4, thus cutting off the supply of pressure fluid to the cylinders *K* and *f*, and completing the cycle of operations.

I claim:

1. In a shank and bit punch, the combination of means for clamping a drill steel, a pin adapted to enter the drill steel, a percussive element to drive the pin into and out of the steel, a feeding element for advancing and withdrawing the punch, a valve chest on the punch, a pressure chamber at one end of the chest, a valve in the chest, and means for exhausting pressure fluid from the pressure chamber for opening the valve to admit pressure fluid to the percussive and feeding elements for advancing the punch and driving the pin into the steel and for automatically returning the punch. 70

2. In a shank and bit punch, the combination of means for clamping a drill steel, a pin adapted to enter the drill steel, a percussive element to drive the pin into and out of the steel, a feeding element for advancing and withdrawing the punch, a valve chest on the punch, a pressure chamber at one end of the chest, a valve in the chest, means for exhausting pressure fluid from the pressure chamber for opening the valve to admit pressure fluid to the percussive and feeding elements for advancing the punch and driving the pin into the steel and for automatically returning the punch. 85

3. In a shank and bit punch, the combination of means for clamping a drill steel, a pin adapted to enter the drill steel, a percussive element to drive the pin into and out of the steel, a feeding element for advancing and withdrawing the punch, a valve chest on the punch, a pressure chamber at one end of the chest, a valve in the chest, foot 100 controlled means for exhausting pressure fluid from the pressure chamber for opening the valve to admit pressure fluid to the percussive and feeding elements for advancing the punch and driving the pin into the steel and for automatically returning the punch. 105

4. In a shank and bit punch, the combination of means for clamping a drill steel, a pin adapted to enter the drill steel, a percussive element to drive the pin into and out of the steel, a feeding element for advancing and retracting the punch, a valve chest on the punch, a pressure chamber at one end of the chest, a controlling valve in 115 the chest for controlling the admission of pressure fluid to the percussive and feeding elements and having a bore in constant communication with a supply of pressure fluid, a port in the valve for constantly admitting pressure fluid from the bore to the pressure chamber, a foot controlled releasing valve at one end of the pressure chamber for releasing pressure fluid therefrom to permit the controlling valve to move to one 120 125 130

end of the chest, a spring to close the releasing valve whereby pressure fluid may be trapped in the pressure chamber for automatically actuating the controlling valve 5 toward the other end of the chest, and means for automatically closing the controlling valve.

5. In a shank and bit punch, the combination of means for clamping a drill steel, a 10 pin adapted to enter the drill steel, a percussive element to drive the pin into and out of the steel, a feeding element for advancing and retracting the punch, a valve chest movable with the percussive element, a pressure chamber associated with one end of 15 the chest, a controlling valve in the chest having two opening positions, said valve

having a bore in constant communication with a supply of pressure fluid, a port in the valve admitting pressure fluid into the 20 said pressure chamber to move the valve to one opening position for retracting the punch, a releasing valve at one end of the pressure chamber for releasing pressure fluid therefrom to enable the controlling valve to be moved to its other opening position for advancing the percussive element, means to open the releasing valve, and means to move the controlling valve to a neutral position for automatically stopping 25 the punch.

In testimony whereof I have signed this specification.

HARRY V. HAIGHT.
